UNITED STATES PATENT OFFICE.

EMIL L. HERRMANN, OF AMHERST, NEBRASKA.

TATTING-SHUTTLE.

1,182,681.

Specification of Letters Patent.

Patented May 9, 1916.

Application filed August 24, 1915. Serial No. 47,105.

To all whom it may concern:

Be it known that I, EMIL L. HERRMANN, a citizen of the United States, residing at Amherst, in the county of Buffalo, State of Nebraska, have invented certain new and useful Improvements in Tatting-Shuttles; and I do hereby declare the following to be a full, clear, and exact description of the invention, such as will enable others skilled 10 in the art to which it appertains to make and use the same.

This invention relates to improvements in shuttles, and particularly to tatting shuttles.

15 One object of the invention is to provide a shuttle which can be quickly and easily filled.

Another object is to provide a shuttle having novel means for holding the thread 20 from being accidentally drawn therefrom, but which can be readily withdrawn by releasing the holding means.

Other objects and advantages will be apparent from the following description when 25 taken in connection with the accompanying drawing.

In the drawing: Figure 1 is a plan view of a shuttle made in accordance with my invention, Fig. 2 is a transverse section on 30 the line 2—2 of Fig. 1, Fig. 3 is a longitudinal section on the line 3—3 of Fig. 1, and Fig. 4 is a section similar to Fig. 2 showing the spring depressed.

Referring particularly to the accompanying drawing, 10 represents the body of the shuttle which is hollow, and has a tapered end 11 and an open end 12 reduced to provide a shoulder 13. Onto this end is engaged a cap 14 having its opposite end tapered in a manner similar to the end 11. Formed in one side of the body is a longitudinal slot 15 which begins at the shoulder 13 and extends a suitable distance toward the other end of the body. At the first- 45 named end of the slot is formed a circular opening 16, one-half of the opening extending into the thicker part of the body, while

the other half is formed in the reduced open end. Formed in the open end of the cap is a notch 17 which registers with the portion of the opening 16 in the reduced end of the body. Disposed within the body and secured adjacent the inner end of the slot 15 is a leaf spring 18 which extends longitudinally under the slot and is provided with a button 19 extending outwardly through the said opening 16. A bobbin 20 is adapted to be filled with thread in the bobbin winder of a sewing machine and then placed in the shuttle.

In filling the shuttle, the spring 18 is depressed by pushing down the button 19, and then inserting through the slot 15 a piece of thread, after which one end of this piece of thread is attached to the end 65 of the thread on the bobbin. The bobbin is then inserted in the shuttle and the cap slipped into place. The spring is again depressed and the piece of thread to which the bobbin thread is attached pulled up 70 through the slot so that the knot is on the outside.

What is claimed is:

A tatting shuttle comprising a hollow body formed with a reduced open end which 75 results in a circumferential shoulder, said body having a longitudinal slot opening through the shoulder where it is formed into a semi-circular recess, a removable cap engaged on the reduced end, a leaf spring 80 secured within the body and extending longitudinally under the slot, and a button carried by the free end of the spring and extending through the recess, said cap having a semi-circular recess formed on its inner end for partially surrounding the said button.

In testimony whereof, I affix my signature, in the presence of two witnesses.

EMIL L. HERRMANN.

Witnesses:

J. T. COLBERT,
S. E. SMITH.
